(57) **CLAIM**

The ornamental design for a vehicle ID holder, as shown and described.

DESCRIPTION

FIG. 1 is a top perspective view of a vehicle ID holder in its closed position;

FIG. 2 is a top view of the vehicle ID holder in its closed position;

FIG. 3 is a bottom view of the vehicle ID holder in its closed position;

FIG. 4 is a front view of the vehicle ID holder in its closed position;

FIG. 5 is a rear view of the vehicle ID holder in its closed position;

FIG. 6 is a right side view of the vehicle ID holder in its closed position;

FIG. 7 is a top perspective view of the vehicle ID holder in its closed position as attached to the dashboard of a vehicle;

FIG. 8 is a top perspective view of the vehicle ID holder in its open position;

FIG. 9 is a top view of the vehicle ID holder in its open position;

FIG. 10 is a bottom view of the vehicle ID holder in its open position;

FIG. 11 is a front view of the vehicle ID holder in its open position;

FIG. 12 is a rear view of the vehicle ID holder in its open position;

FIG. 13 is a right side view of the vehicle ID holder in its open position; and,

FIG. 14 is a top perspective view of the vehicle ID holder in its open position and holding ID papers as attached to the dashboard of a vehicle.

Left side views not shown are mirror images of right side views. Any broken lines illustrative of environmental structure in the drawings are not part of the design sought to be patented.

1 Claim, 9 Drawing Sheets
